UNITED STATES PATENT OFFICE.

JOHN J. NAUGHTON, OF PEEKSKILL, NEW YORK.

TIME-CONTROLLED STOVE-LIGHTER.

1,314,354.

Specification of Letters Patent. Patented Aug. 26, 1919.

Application filed May 12, 1917. Serial No. 168,219.

To all whom it may concern:

- Be it known that I, JOHN J. NAUGHTON, a citizen of the United States, residing at Peekskill, in the county of Westchester and State of New York, have invented certain useful Improvements in Time-Controlled Stove-Lighters, of which the following is a specification, reference being had therein to the accompanying drawing.
- 10 This invention has reference generally to improvements in that class of inventions known as time controlled mechanism and more particularly relates to a time controlled stove lighter.
- 15 As the primary aim and object this invention contemplates the provision of a novel attachment on a stove or the like for receiving a match and with which coöperates novel means for striking and igniting
- 20 the match so that it may subsequently be projected into the stove at a point near the burner therein by the match receiving and supporting means so as to consequently light the burner at a predetermined time.
- 25 It is an additional and equally important object of this invention to provide time controlled spring actuatable means for removably holding the match striking means in a raised position, the latter being releasable at a predetermined time so as to consequently ignite the match and permit of the actuation of the match projecting means.
- 30 As an additional object the invention consists in the provision of novel means oper-
- 35 ably connected with the hour shaft of the clock for removing the retaining pin from the path of movement of the spring actuatable means at the proper time so as to consequently release the match striking means.
- 40 More particularly, the present invention embraces the provision of novel supporting means for guiding the movement of the match striking means and the match receiving means so as to assure of an effective
- 45 operation of the parts.

As a further improvement this invention includes the provision of novel means for removably holding the match striking means in an inactive position and also the provision of novel means for releasably holding the match projecting means in an inactive position.

The invention, as a still further object, resides in the provision of a novel clasp for holding one of the arms of the resilient actu-

atable releasing means against the time controlled retaining pin.

More specific objects of this invention include the provision of improved means for supporting the clock and for removably connecting the supporting means to the support; to provide a removable match striking plate; and to so construct the main support so that the several successively actuated parts will be assured of an effective 65 operation.

Among the other aims and objects of this invention may be recited the provision of a device of the character mentioned with a view to compactness, and in which the number of parts are few, the construction simple, the cost of production low and the efficiency high.

Other improvements and novel details in the construction and arrangement of the various parts of the apparatus will be brought out more in detail in the description to follow which for a clear understanding of the invention should be considered in connection with the accompanying drawings forming a part hereof, and wherein is disclosed for the purpose of illustration a convenient and satisfactory embodiment of the invention. It is to be noted in this connection that various minor changes in the construction and arrangement of parts may be made without departing from the spirit of the invention or the principle of operation of the various parts.

The preferred embodiment of the present invention is clearly illustrated in the accompanying drawings, in which:

Figure 1 is a front elevation of the device attached to a stove;

Fig. 2 is a rear elevation thereof partly in section;

Fig. 3 is a side elevation of the invention;

Fig. 4 is a front elevational detail of the clock mechanism;

Fig. 5 is a vertical section on line 5—5 of Fig. 4;

Fig. 6 is a sectional detail of the main support and the match striking and projecting means;

Fig. 7 is an enlarged fragmental section on line 7—7 of Fig. 1;

Fig. 8 is a fragmental top plan of the device;

Fig. 9 is a perspective detail of the time controlled retaining pin;

Fig. 10 is a perspective detail of the spring actuatable releasing arms.

Similar reference characters are employed in all of the above described views, to indicate corresponding parts.

Referring now, more particularly, to the accompanying drawings there is provided a stove body 1 of any conventional form in which is mounted a burner 2 while attached 10 exteriorly of the body is the improved time controlled stove lighter indicated in its entirety by the numeral 3, being preferably supported with respect to the body by improved attaching brackets 4 and 5.

15 The stove lighter in the present instance consists of a main support formed preferably of a single piece of material including a base 6 from the inner end of which projects an upright arm 7 while another arm 8 projects from the upper end thereof at approximately right angles thereto being positioned directly over the base 6. A guiding tube 9 has one end connected to the outer surface of the upright portion about the 25 opening 10 therein, the tube extending horizontally from the upright portion and projecting through an opening 11 in the stove body 1 and terminating near the burner 2. A collar 12 is arranged about the tube and is connected to the outer face of the upright portion by means of suitable fastening devices 13 and serves to hold the tube rigid with respect to the upright portion. A vertical supporting tube 14 is mounted on the 30 upper surface of the arm 8 about an opening 15 formed through and adjacent the outer end of the arm. A collar 16 is arranged about the tube and is connected to the upper surface of the arm by suitable fastening devices 17 and serves to effectively support the tube. A supporting platform 18 of a 35 rectangular form is mounted on the upper end of the tube 14 while a collar 19 is arranged about the tube and is connected to the under surface of the platform by means of suitable fastening devices 20 so as to effectively connect these parts together. Opposed flanged guides 21 are mounted on the upper surface of the platform for a purpose that will presently appear and likewise 40 a stop 22 is arranged transversely to the upper surface adjacent one end of the platform. The upper bracing bracket 4 has its respective ends connected to the under surface of the platform and to the body 1 by suitable fastening devices 24.

With a view toward providing the improved match receiving and supporting means a substantially U-shaped guide 25 is 45 rigidly connected to the outer end of the base 6 while movably arranged therebetween is a supporting tube 26, having a longitudinal slot 27 therein. A match receiving and supporting element in the form of a rod 28 is 50 slidably mounted in the tube 26, the outer

end thereof being provided with a match receiving socket 29 for receiving and retaining a match while a head 30 is formed on the inner end thereof. Suitable resilient means such as a contractile coil spring 31 is arranged within the tube 26 about the rod 28 and has its respective ends connected to inner end of the tube and to the head, the tension of the spring tending to normally hold the head toward the inner end of the slot. 70 A setting arm 32 extends laterally from the head and is slidably mounted in the slot 27 being adapted for engagement with the right angularly extending end 33 of the outer end of the slot so as to normally retain the match 75 supporting member in an inactive position. A plug 34 serves to removably close the outer end of the tube 26 while a strip 35 is mounted on the outer surface of the tube adjacent the inner end of the slot and serves 80 to reinforce the tube at this point. By this arrangement it will be appreciated that when the tube 26 lies flat upon the upper surface of the base 6 and longitudinally thereof and the arm 32 is drawn toward the outer 85 end of the slot 27 and released the rod 28 will be, owing to the action of the spring 31, slid through the tube 26 and also through the tube 9 which is arranged in alinement therewith. This action of course projects 90 the match into the stove and holds it above the wick burner 2.

As intimated improved means have been provided for striking the match preparatory to projecting it. In reducing this feature of the invention to practice an elbow joint 36 is mounted on the inner end of the tube 26 and also about the rod 28. Another rod 37 is slidably mounted in the tube 100 14 while the lower end is rigidly connected to the elbow joint 36. A head 38 is carried by the upper end of the rod 37 while a setting arm 39 extends laterally from the head and operates in a vertical bayonet slot 40 in the tube. The upper end 41 of such slot is 105 of course arranged at right angles to the main portion thereof so that the arm 39 may engage the portion 41 of the slot. Since the rod 37 is connected to the tube 26 through the medium of the elbow joint 36, any turning 110 of the rod 37 on its axis will result in an angular movement of the tube 36 in the plane in which it lies. When the setting arm 39, therefore, is moved into the upper end 41 of the slot 40, such a turning of the 115 rod 37 on its axis is effected with the result that the tube 26 and those parts associated with it are swung at an angle with respect to the main support of the device. This action results in the rod 28 having its 120 receiving socket 29 so positioned that a match may be inserted therein without interference from the upright arm 7 of the main support. Of course the rod 28 during such operation must be locked against move- 125 130

ment in the tube 26 and the setting arm 32, therefore, engages in the right angularly disposed end of the slot 27 formed in the tube 26. The rod 37 is under tension of suitable resilient means such as a contractile coil spring 42 the respective ends of which are connected to the head 38 and to the lower end of the tube 14. This spring serves to force the rod downwardly when the setting arm 39 is released in a manner that will become hereinafter apparent.

Coöoperating with the match supporting means and the match striking means is a match striking plate 43. This plate is of a rectangular configuration and is adapted to be removably arranged between guides 44 which are carried respectively on the under surface of the arm 8 on the upper surface of the base 6 in closely spaced relation to the inner surface of the upright portion 7. The outer face of the plate is roughened as indicated by the numeral 45 while the lower end thereof is provided with an aperture 46 which registers with the opening 10 in the upright portion. A lip 47 serves to limit sliding movement of the plate so as to properly register its aperture with the opening 10.

Slidably and removably mounted on the upper surface of the platform 18 between the guides 21 is a base plate 48 on which is supported a clock 49 by means of brackets 50. A spring actuatable means for releasably retaining the setting arm 39 in a raised position is operatively connected with the clock and consists in this instance of a tubular casing 51 carried by the under surface of a clock transversely thereof by means of supporting brackets 52. A rod 53 is carried within the casing 51 while a coil spring 54 is arranged about the rod and has one end connected to the rod and the other end connected to the casing to enable an attendant to place the rod 53 under the tension of the spring 54. An arm 55 has one end removably connected to one end of the rod 53 by means of a nut 56 while the outer end is curved and terminates in a hook 57, the bill of which is adapted to engage the setting arm 39 to hold the rod 37 in a raised or set position as shown in Fig. 1. An arcuate or semi-circular arm 58 has its inner end rigidly clamped to the opposite end of the rod 53 by means of a clamping nut 59 while the arm extends in an opposite direction to the direction assumed by the arm 55. A lug 60 is formed on the outer terminal of the arm 58 while a handle 61 is connected to the arm so that it may be set when desired. In order to limit the outward swinging movement of the arm 58 and also the movement of the arm 55 an arcuate strip 62 is connected to the rear face of the clock 49 by suitable brackets 63. A retaining pin 64 is slidably mounted through an opening 65 in the rear face of the clock 49 and also through a registering

opening 66 in the strip being operably connected to the clock mechanism in a manner to be described. This pin projects beyond the outer face of the strip and lies in the path of movement of the lug 60 to prevent actuation of the arm 58 and in so doing serves to hold the arm 55 in a substantially vertical position so that the latter may hold the setting arm 39 in a raised position until the pin is moved inwardly which action releases the arm 58 and allows the spring 54 to release the arm 55 from the setting arm 39. A lug 67 is formed on that end of the strip 62 remote from the lug 64 and is engaged by the lug 60 so as to limit the outward swinging movement of the arm 58. Suitable means such as a pivotally mounted resilient catch 68 on the end of the strip 62 opposite the lug 67 is employed for bearing against the outer face of the arm 58 to prevent accidental disengagement of the lug 60 from the pin 64, such as would occur were the arm 58 allowed to spring outward from the clock case.

With a view toward providing the novel means for operably connecting the retaining pin 64 to the clock mechanism so that the actuation of the spring actuated releasing means will be controlled by the clock and actuated at a predetermined time a spring plate 68' is mounted on the outer face of one plate of the frame 69 and has pivotally connected to the upper angularly bent end thereof by means of a suitable fastening device 70 the inner end of the retaining pin 64. The under surface of the said plate is provided with a recess 71 so that the plate may be arranged around the setting shaft 72 rotatably mounted in the frame. This plate normally acts against a gear 73 loosely mounted on the shaft 72 and is operably connected to the hour shaft 74. A collar 75 is also carried by the outer face of the gear 73 and has the outer edge thereof provided with a notch 76. A disk 77 is carried by the shaft 72 while a lug 78 projects from the periphery thereof and coöperates with the notch 76. A setting hand 79 is carried by the outer projecting end of the shaft 72 and is arranged in alignment with the lug 78. A knurled wheel 80 is carried by the opposite end of the shaft 72 and enables the attendant to properly adjust the hand 79 on the setting dial 81 marked on the main dial 82. The minute hand 83 and the hour hand 84 of the clock 49 of course operate in the usual manner. By this arrangement it will be appreciated that when the lug is engaged on the outer edge of the collar 75 the pin 64 will be projected through the openings 65 and 66 so as to be engaged by the lug 60 and when the hour and minute hands reach the point at which they are set, owing to the alignment of the setting hand 79 with the lug 78 and the fact that the gear 73 moves with the hour 130

hand and carries the collar 75 the notch and the lug will be alined and forced into engagement with each other by the spring plate 68', the movement of which of course draws the pin 64 inwardly so as to release the arms 58 and 55 and consequently the match scratching and match projecting means.

The mode of operation of the present invention may be reviewed as follows:

- 10 Assuming that the parts have been assembled in the manner described the attendant engages the setting arm 32 and moves it toward the outer end of the slot 27 so as to removably lock the arm in the angularly bent end 33 of the slot. This action expands the coil spring 31 and draws the rod 28 inwardly. The setting arm 39 is now raised in the slot 40 against the tension of the spring 42 and moved in the right angled end 41 so as to partially rotate the rod 37 and hold it in a set position. During the partial rotation of the rod the tube 26 is raised from engagement between the guides and swung to a position, so that a match 20 may be inserted in the socket 29, as before described. The stem of the match is frictionally held in the socket 29 so that the head is arranged at the outer end of the socket. The knurled wheel 80 is now actuated to adjust the setting hand for instance at six o'clock and of course the lug 70 is correspondingly adjusted. This action moves the pin 64 outwardly through the openings 65 and 66 whereupon the handle 30 35 40 45 50 55 60 65 70 75 80 85 90 95 100 105 110 115 120 125 130 135 140 145 150 155 160 165 170 175 180 resilient means for moving the match supporting and projecting member into a position with alinement to the said rigidly mounted tube, whereby the match will be ignited from friction with the striking plate and subsequently projected into the stove through the aforesaid tube.

3. A device of the character described including a match supporting and projecting member, means for slidably receiving and supporting the match supporting and projecting member, a slidably mounted rod connected at right angles to the match receiving and supporting means, an arm projecting from the rod, a plate having a match striking surface and an opening, spring actuated means for releasably holding the arm to consequently hold the rod in a raised position, time controlled mechanism for releasing the spring actuated means to consequently release the rod, resilient means for sliding the rod downwardly subsequent to the release, and resilient means for normally holding the match receiving and supporting member so that a match may be held yieldingly against the striking surface of the plate preparatory to releasing the rod and for projecting the match supporting and projecting member through the opening in the match scratching plate subsequent to the release of the match supporting and projecting member.

4. A device of the character described, including a support adapted to be connected to a stove, a slotted tube mounted on top of the support, a guiding tube projecting from the support and adapted to be arranged adjacent the stove burner, a plate mounted on the support and provided with a match scratching surface and with an opening in alinement with the guiding tube, another tube provided with a longitudinal slot, a match supporting and projecting member resiliently mounted in the second mentioned slotted tube, a resiliently mounted rod in the first mentioned slotted tube and having the lower end connected to the second slotted tube, an arm projecting from the rod, spring actuated means for releasably engaging the arm to consequently hold the match supporting and projecting member in a raised position and in yielding engagement with the match striking surface of the plate, and time controlled mechanism for releasing the spring actuated means to consequently release the arm and ignite a match in the supporting member preparatory to

the projection thereof through the guiding tube.

5. A device of the character described including a resiliently mounted match supporting and projecting member, a tubular casing, a rod mounted therein, resilient means for holding the rod under tension, an arm projecting from one end of the rod for removably holding the match supporting and projecting member in a raised position, another arm carried by the other end of the rod, a lug on the outer end of the last mentioned arm, a time actuated retaining pin for removable engagement with the lug on the last mentioned arm, and means for limiting the movement of the last mentioned arm subsequent to release.

6. A device of the character described including a resiliently mounted match supporting and projecting means, a rigidly mounted tubular casing, time controlled mechanism mounted adjacent the tubular casing, a rod carried in the casing, an arcuate arm carried at one end of the rod, a lug on the outer end of the arm, a pin operably connected to the time controlled mechanism and actuated at a predetermined time for coöperation with the lug for releasably holding the arm, resilient means for holding the rod in the casing under tension, means for limiting the outward swinging movement of the arm subsequent to release, and a hook like arm carried by the other end of the rod for releasably holding the match supporting and projecting means in a set position.

7. A device of the character described including horizontally disposed and vertically slidably receiving means, horizontally slidable match supporting and projecting means resiliently mounted in the receiving means, a match scratching plate rigidly mounted in advance of the receiving means, spring actuated means for releasably holding the receiving means in a raised position, time controlled mechanism, a retaining pin slidably mounted in the time controlled mechanism for coöperation with the spring actuated means, and means for operably connecting the slidably mounted pin to the time controlled mechanism so that the pin will be actuated at a predetermined time to release the spring actuated means to permit the operation of the receiving means and the match supporting and projecting means.

In testimony whereof I affix my signature.
JOHN J. NAUGHTON.
